[57] CLAIM

The ornamental design for a shaped food product, as shown and described.

DESCRIPTION

FIG. 1 is a perspective view of an embodiment of the shaped food product;

FIG. 2 is a plan view of the shaped food product of FIG. 1;

FIG. 3 is a left side view of the shaped food product of FIG. 1;

FIG. 4 is a right side view of the shaped food product of FIG. 1;

FIG. 5 is a bottom view of the shaped food product of FIG. 1;

FIG. 6 is a front end view shaped food product of FIG. 1;

FIG. 7 is a bottom end view of the shaped food product of FIG. 1;

FIG. 8 is a plan view of a further embodiment of the shaped food product of FIG. 1;

In this embodiment, a coarse granular edible topping, e.g. nuts, particulate ready-to eat cereal, or other similar coarse granular toppings are deposited on the top surface of the shaped food product.

FIG. 9 is a left side view of the embodiment of FIG. 8;

FIG. 10 is a right side view of the embodiment of FIG. 8;

FIG. 11 is a top end view of the embodiment of FIG. 8;

FIG. 12 is a bottom end view of the embodiment of FIG. 8;

FIG. 13 is a plan view of an alternative embodiment of the shaped food product of FIG. 1 having a fine granular topping, e.g. cinnamon, applied on the top surface thereof;

FIG. 14 is a left side view of the embodiment of FIG. 13;

FIG. 15 is a right side view of the embodiment of FIG. 13;

FIG. 16 is a top end view of the embodiment of FIG. 13; and,

FIG. 17 is a bottom end view of the embodiment of FIG. 13.
